W. F. EMERSON.
COLLAPSIBLE CONTAINER FOR GREASE CUPS.
APPLICATION FILED SEPT. 26, 1917.

1,286,875.

Patented Dec. 3, 1918.

UNITED STATES PATENT OFFICE.

WILLIAM FREDERICK EMERSON, OF BUFFALO, NEW YORK, ASSIGNOR TO BUFFALO METAL GOODS COMPANY, OF BUFFALO, NEW YORK, A CORPORATION OF NEW YORK.

COLLAPSIBLE CONTAINER FOR GREASE-CUPS.

1,286,875.

Specification of Letters Patent. Patented Dec. 3, 1918.

Application filed September 26, 1917. Serial No. 193,339.

To all whom it may concern:

Be it known that I, WILLIAM F. EMERSON, a citizen of the United States, residing at Buffalo, in the county of Erie and State of 5 New York, have invented new and useful Improvements in Collapsible Containers for Grease-Cups, of which the following is a specification.

This invention relates to collapsible containers for lubricating grease and consists 10 of an improved form thereof adapted protectively to inclose a charge of grease and designed particularly to permit of its successful use with standard forms of grease 15 cups.

Attempts have been made to employ lubricating grease put up in collapsible containers in capsule form each containing a proper charge of the lubricant for the grease cup 20 in which it is to be used thereby providing a desirable and convenient means for charging the grease cups without spreading the grease where not desired and avoiding the wastage and soiling of the hands and clothing incident thereto. However these attempts have been commercially unsuccessful, 25 particularly in connection with the simple type of grease cup largely used on automobiles consisting of a fixed base member providing an entry passage for the grease and having threaded thereon a cap or cup member which compresses and feeds the grease as it is threaded down on the base. The reason for this failure resides in the fact that 30 the collapsible containers heretofore used were of such form that in most instances upon compressing the containers to discharge the grease the material of the containers is forced outwardly into contact with 35 the internal threads of the cup. As a result it becomes difficult and sometimes impossible to screw down the cap by hand to feed the grease and moreover, the containers become torn and adhere to the cap to such a 40 degree that it is only with difficulty that they can be removed.

According to my present invention I provide that the collapsible container, which 45 may be of any suitable material, shall be of an improved form which upon being subjected to pressure to expel the grease will in collapsing fold inwardly so as to avoid extrusion of the folds into contact with the threaded walls of the cap. This I desirably 50 accomplish by forming the container with

inclined side walls converging toward the bottom or closed end thereof which is of smaller diameter than the opposite and open end. The open end of the container is desirably of a form particularly adapting it to 60 receive a removable closing cap for protecting the grease until placed in the cup. As a result of forming the container of this improved arrangement the aforesaid objections are overcome and the lubricant may 65 successfully be used in capsule form as the crushed containers fold inwardly and out of contact with the cap so that upon removal of the cap the crushed container may be easily expelled.

The described and other features and advantages of my invention will be understood by reference to the drawing herewith wherein there is shown a desirable embodiment of my invention and wherein the reference numerals of this description are applied to the corresponding parts in the several views.

Referring to the figures, Figure 1 is a view in side elevation illustrating an approved form of container of my invention with the 80 protecting cap thereon. Fig. 2 is a plan view thereof with the cap removed and Fig. 3 is a side elevation of the container in inverted position. Figs. 4 and 5 and 6 illustrate the manner in which the containers 85 fold as the grease is expelled as used in a standard form of grease cup. Fig. 4 shows the cap in position with a full charge of grease; Fig. 5 is an advance position and in Fig. 6 the cap is removed, illustrating the 90 fully collapsed capsule. Fig. 7 illustrates my improved type of capsule being used in a modified type of grease cup.

Figs. 1 to 3 of the drawings illustrate an approved form of my invention which consists in forming the grease container of suitable collapsible and grease proof paper or other material and of the cup shape as shown. The container 1 is formed to be of cup shape with a closed bottom 2 and has 100 its side wall 3 inclined as shown for the greater part of its length and provided with a marginal top portion 4 which is straight sided to provide a perfect fit for a one piece removable cap 5 fitted thereon as shown to 105 protect the lubricant 6 therein during transportation. As will be understood these capsules of grease so formed, are proportioned to provide a proper charge of lubricant for the grease cup in which they are to be used. 110

In Figs. 4, 5 and 6 I have illustrated the action of my improved container in this connection showing its use in the conventional type of automobile grease cup referred to wherein the cap member 7 is internally threaded and screws down onto the base member 8 as shown and as it is screwed down thereon acts as a plunger to discharge the grease through the opening 9 in the base. 10 As indicated, when the capsule is to be used the cap 5 is removed and the container 1 is placed in the base member 8 in inverted position as shown in Fig. 4 with the open end 10 of the container directed toward the discharge opening 9 of the base. The grease cup cap 7 is then placed thereover and threaded onto the base member 8. Thereafter upon screwing down the cap 7 the container 1 will be collapsed and the grease 15 forced out through the opening 9 into the bearing to be lubricated.

As shown in Figs. 5 and 6, by reason of the incline of the side wall of the container 1, upon being crushed, the side wall 3 will 20 collapse inwardly so that the resulting folds thereof will not come in contact with the internal threads 12 of the caps. The collapsed container is thus free of contact with the plunger cap 7 which permits removal of the latter leaving the crushed container or envelop on the base so that it may readily be pushed off and discarded without soiling of the hands. By the resulting non-engagement of the collapsed containers of my invention there is eliminated any necessity of 25 providing special means to retrieve the crushed capsule from adhering within the interior of the grease cup cap as has heretofore been proposed. My improved form of 30 grease container therefore provides for its successful use in a standard type of grease cup, hundreds of thousands of which are in use:

In Fig. 7 I have illustrated my improved 45 container in another and special form of grease cup wherein the base portion 8 is formed with a groove 19 into which the envelop engages to retain it on the base portion when the cap 7 thereof is removed. This arrangement is desirable when the grease cup 50 is supported in other than the vertical position.

As will readily be understood, the container of my invention may be modified in 55 many respects without departing from my invention. It is therefore intended that all matter contained herein shall be interpreted as illustrative and not in a limiting sense.

Having described my invention, I claim, 60 1. In a device of the character described, the combination of a grease cup comprising a base having a passage for the grease and a second member movable with relation thereto, of a collapsible grease container having 65 a cup shaped body portion adapted to be in-

terposed between the base and movable member, said container having an opening directed toward the base member and a closed upper end and having its body portion formed to promote folding inwardly of its 70 side wall when subjected to pressure by the movable member, substantially as described.

2. In a device of the character described, the combination of a grease cup comprising a base provided with an outlet passage for 75 the grease and a second member movable with relation thereto, of a collapsible grease container having a charge of grease therein adapted for use therewith, said container being of cup-shaped form and provided with 80 a closed wall at one end and with an opening at its other end arranged to communicate with the outlet passage of the base member and said container having a portion of 85 its side wall inclined to promote folding inwardly thereof when collapsed under pressure in the cup.

3. In a device of the character described, the combination of a grease cup comprising a base provided with an outlet passage for 90 the grease and a second member movable with relation thereto, of a collapsible grease container having a charge of grease therein adapted for use therewith, said container being of cup-shaped form and provided with 95 a closed wall at one end and with an opening at its other end arranged to communicate with the outlet passage of the base member, said container having a portion of its side wall inclined to promote folding inwardly 100 thereof when collapsed under pressure in the cup and said side wall being formed adjacent the open end with a marginal straight sided portion adapted to receive thereon a separable protective cap.

4. In a device of the character described, the combination of a grease cup comprising a base provided with an outlet passage for the grease and pressure exerting means for expelling the grease therefrom, of a collapsible grease container having a charge of 110 grease therein adapted to be received within the cup, said container being of cup shaped form and having an outer closed end and an inner open end communicating with the outlet passage of the base, said container being formed with its outer closed end of smaller diameter than its open end and with its side wall inclined to promote folding inwardly 115 thereof when collapsed under pressure in the 120 cup.

5. In a device of the character described, the combination with a grease cup comprising a base member having an outlet passage therethrough for the grease, and a cap member threaded thereon and adapted to be screwed down onto the base to expel the grease from within the cup, of a collapsible grease container having a charge of grease 125 therein adapted to be received within the 130

- cup, said container being of cup shaped form and having an outer closed end and an inner open end communicating with the outlet passage of the base, said container being 5 formed with its outer closed end of smaller diameter than its open end and with its side wall inclined to promote folding inwardly thereof when collapsed under pressure in the cup.
- 10 6. In a device of the character described, the combination with a grease cup comprising a base member having an outlet passage therethrough for the grease, and a cap member threaded thereon and adapted to be 15 screwed down onto the base to expel the grease from within the cup, of a collapsible grease container having a charge of grease therein adapted for use therewith, said container being of cup-shaped form and provided with a closed wall at one end and with an opening at its other end arranged to communicate with the outlet passage of the base member and said container having a portion of its side wall inclined to promote folding 25 inwardly thereof when collapsed under pressure in the cup.
7. In a device of the character described, the combination with a grease cup comprising a base member having an outlet passage therethrough for the grease, and a cap member threaded thereon and adapted to be 30 screwed down onto the base to expel the grease from within the cup, of a collapsible grease container having a charge of grease therein adapted for use therewith, said container being of cup-shaped form and provided with a closed wall at one end and with an opening at its other end arranged to communicate with the outlet passage of the base 35 member and said container having a portion of its side wall inclined to promote folding inwardly thereof when collapsed under pressure in the cup, and said side wall being formed adjacent the open end with a mar-
- ginal straight sided portion adapted to receive thereon a separable protective cap.
8. In a device of the character described, the combination of a grease cup comprising a base having a passage for the grease and a second member movable with relation thereto, of a collapsible grease container having a cup shaped body portion adapted to be interposed between the base and movable member, said container having an opening directed toward the base member and a closed upper end and having its body portion formed to promote folding inwardly of its side wall when subjected to pressure by the movable member, and means on the base member adapted to be engaged by the collapsed capsule to retain the latter thereon.
9. In a device of the character described, the combination with a grease cup comprising a base member having an outlet passage therethrough for the grease, and a cap member threaded thereon and adapted to be 65 screwed down onto the base to expel the grease from within the cup, of a collapsible grease container having a charge of grease therein adapted to be received within the cup, said container being of cup shaped form and having an outer closed end and an inner open end communicating with the outlet passage of the base, said container being formed with its outer closed end of smaller diameter than its open end and with its side wall inclined to promote folding inwardly thereof when collapsed under pressure in the cup, and means on the base member adapted to be 70 engaged by the collapsed capsule to retain the latter.
- In testimony whereof I have signed my name to this specification.

WILLIAM FREDERICK EMERSON.
